WALL CALENDAR

Filed June 28, 1930

UNITED STATES PATENT OFFICE

ARTHUR J. STEVENS, OF JOLIET, ILLINOIS

WALL CALENDAR

Application filed June 28, 1930. Serial No. 464,589.

My invention relates to calendars, and it particularly has reference to those which are usually hung up or otherwise mounted on a wall.

5 The invention has for an object to provide a new and useful daily date calendar that permits the purchasers of the calendars to purchase from year to year, only the calendar pads, placing them on the backs which they 10 had previously used or distributed.

Further it is an object to provide a back to be mounted on the wall and a pad attached to the back, the sheets of which pad may be torn off, one by one, as desired, the construction of the pad mounting means being such 15 that the sheets of the pad cannot be so tightly secured as to prevent their being easily removed one at a time.

Further it is an object to provide a calendar whose pad fastening devices are so designed as to permit the user to replace his old pad with a new one with the utmost ease and without removing bolts, sleeves or the calendar back.

25 Further it is an object of the invention to provide a pad fastening device of such construction that during the process of assembly by the manufacturer the assembler cannot fasten the pads so tightly that the first few 30 sheets pulled away will not come away with ease.

Another object of my invention is to make a pad fastening device which is simple, compact, inexpensive and attractive in appearance.

Another object of my invention is to provide against any possibility of the bolt where it passes through the nut at the back of the calendar from projecting beyond the plane 40 of the nut and forcing itself through the mailing container in which the calendars are shipped.

Other objects will in part be obvious and in part be pointed out hereinafter.

45 To the attainment of the aforesaid objects and ends, my invention consists in the novel features of construction and in the combination, connection and arrangement of parts, hereinafter more fully described, and then 50 pointed out in the appended claims.

In the drawings:

Figure 1 is a perspective view showing how a pad is placed on the back.

Figure 2 is an enlarged detail vertical section through one of the mounting devices.

In the drawings, in which like numerals of reference indicate like parts in all of the figures, 8 represents the back which may be of any desired construction, and preferably provided with spaces for advertising matter, 60 as is the usual custom. Secured to the back 8 is one or more fastening means for the pads 3. The fastening means comprise spindles 4 each having a flange 2 (fixed or removable) adjacent one end, that portion 65 of the end of the spindle which projects beyond the fixed flange being threaded to receive a securing nut 1 and also being adapted to pass through a suitable hole in the back 8, the length of the threaded portion being 70 such that when the nut is tightened home its exposed face and that of the end of the threaded portion of the spindle will be flush, as shown best in Figure 2 of the drawings.

The spindle 4 has a reduced threaded 75 portion 5 thereby providing a shoulder against which the end 6 of the screw head 7 may abut, the screw head 7 being bored and tapped to fit on the threaded portion 5 of the spindle 4.

The length of the spindle 4 from flange 2 to the shoulder 9 adjacent the threaded portion 5 is of a fixed length equal to the thickness of the pad 3 which it is designed to receive, so that when the screw head 7 is 85 screwed home tightly it will not jam the leaves of the pad 3 so tightly as to prevent the ready tearing off of the top sheets of the same when desired.

While my invention is particularly useful in connection with calendar pads it is obvious that it may be employed in any case where a pad of sheets is mounted on a back.

The invention is especially useful, however, in advertising daily calendar pads because it enables one to purchase a set of backs and pads for distribution to his clientele and then in subsequent years simply furnish the clientele with the pad replacements. Thus the backs remain useful from 95 100

year to year and the advertisements thereon become fixed or established in the places where the calendars are used.

Other advantages of the invention will be clear to those skilled in the art.

What I claim is:

1. A flat back to lie against a wall parallel thereto, a pad, means to mount said pad on said back, said mounting means comprising at least one spindle having a flange adjacent one end, said one end being threaded, said back having a hole through which said threaded end is passed, and a clamp nut on said threaded end for securing said spindle to the back, and removable means on the other end of said spindle for holding the pad in place said spindle having its external surface smooth throughout that portion of its length which passes through the pad.

20 2. A flat back to lie against a wall parallel thereto, a pad, means to mount said pad on said back, said mounting means comprising at least one spindle having a flange adjacent one end, said one end being threaded, said back having a hole through which said threaded end is passed, and a clamp nut on said threaded end for securing said spindle to the back, and removable means on the other end of said spindle for holding the pad in place, the length of said threaded end being not greater than the combined thickness of the back and nut said spindle having its external surface smooth throughout that portion of its length which passes through the pad.

30 3. A flat back to lie against a wall parallel thereto, a pad, means to mount said pad on said back, said mounting means comprising at least one spindle having a flange adjacent one end, said one end being threaded, said back having a hole through which said threaded end is passed, a clamp nut on said threaded end for securing said spindle to the back, the other end of said spindle having a shoulder and a threaded portion projecting beyond the shoulder, and a screw head threaded on said threaded portion to abut said shoulder said spindle having its external surface smooth throughout that portion of its length which passes through the pad.

40 4. A flat back to lie against a wall parallel thereto, a pad, means to mount said pad on said back, said mounting means comprising at least one spindle having a flange adjacent one end, said one end being threaded, said back having a hole through which said threaded end is passed, a clamp nut on said threaded end for securing said spindle to the back, the other end of said spindle having a shoulder and a threaded portion projecting beyond the shoulder, and a screw head threaded on said threaded portion to abut said shoulder, the length of said first mentioned threaded end being not greater

than the combined thickness of the back and nut said spindle having its external surface smooth throughout that portion of its length which passes through the pad.
